UNITED STATES PATENT OFFICE

154,258

DESIGN FOR A HURRICANE LAMP

Albert E. Frontier, Des Plaines, Ill.

Application November 29, 1947, Serial No. 142,884

Term of patent 3½ years

(Cl. D48—20)

To all whom it may concern:

Be it known that I, Albert E. Frontier, a citizen of the United States, residing at Des Plaines, Illinois, have invented a new, original, and ornamental Design for a Hurricane Lamp, of which the following is a specification, reference being had to the accompanying drawing, forming part thereof.

Figure 1 is a perspective view of a hurricane lamp, showing my new design;

Figure 2 is a side elevational view thereof.

The characteristic features of my design reside in the portions shown in full lines.

I claim:

The ornamental design for a hurricane lamp, as shown and described.

ALBERT E. FRONTIER.
